UNITED STATES PATENT OFFICE.

LLOYD C. REEDER, OF SALEM, WEST VIRGINIA.

CHECK-BOOK.

No. 888,352.

Specification of Letters Patent.

Patented May 19, 1908.

Application filed May 3, 1907. Serial No. 371,615.

To all whom it may concern:

Be it known that I, LLOYD C. REEDER, a citizen of the United States of America, residing at Salem, in the county of Harrison 5 and State of West Virginia, have invented new and useful Improvements in Check-Books, of which the following is a specification.

This invention relates to check books, and 10 one of the principal objects of the same is to provide convenient and reliable means for keeping the cash accounts of business houses in their dealings with the bank and with their patrons.

15 Another object of the invention is to provide a check book that will temporarily bind a number of check blanks, and will hold in position a series of independent stubs which will indicate all money transactions of the 20 business, the amounts withdrawn by check from the bank, the amounts deposited, and the bank balance.

These and other objects may be attained by means of the construction and arrangement 25 illustrated in the accompanying drawing, in which:

Figure 1 is a plan view of the open check book, and showing one of the covers of the book broken away. Fig. 2 is a plan view of 30 the stub portion of the check. Fig. 3 is a vertical sectional view of the back portion of the book in closed position. Fig. 4 is a detail plan view of one corner of the book. Fig. 5 is a sectional view of the book back 35 and two covers, the latter being shown broken away. Fig. 6 is a sectional view of one of the independent stubs, and showing the reinforcing strip through which the binder staple is adapted to be passed.

40 Referring to the drawing for a more particular description of my invention, the numerals 1 designate the covers of the book and 2 is a flexible leather back which forms a hinge for the covers, said back being connected to the covers 1 by an adhesive substance like glue, and riveted to the top and bottom of the back are metal strips 3 disposed upon the outside, the rivets 4 passing through the metal strips 3 through the back 45 2 through a lining 5 and through interior metal strips 6 to give stability to the book. The metal plates 7 are of substantially the same length as the slots 8 and said plates extend through said slots and are bent down 50 upon opposite sides of the cover members. The metal plates 7 are provided with por-

tions which extend through the slot 8 and thus bind the walls of said slot. A binding loop or staple 9 is connected to the back 2 by means of removable bolts or pins 10, said pins 60 extending through eyes in the ends of the loop or staple 9, and through the book back and metal strips, said bolts being fitted with a winged nut 11 for holding the metal loops in place and to permit them to be removed. 65 The binding loop or staple 9 passes through the slot 8 and the sides of said loop bear against the metal plates 7. A series of blank checks 12 are provided with perforations at their inner ends for connection with the loops 70 9. The checks 12 are provided with the usual stubs 13. A series of independent stub sheets 14, each provided with a reinforcing strip 15 which is perforated at 16, is connected to the loops 9 on top of the check 75 blanks 12. The stub sheets 14 each contain a date line, a name line, an article line, and an amount line, together with the words "Debit" and "Credit," so that all the money transactions of the business may be entered in 80 this column. At the right of the column referred to is a column headed "Checks" and at the right of this column is a column headed "Deposits." At the right of this column is a column headed "Balance." In the first column at the top the word "Forwarded" appears. 85 This column is indicated by the numeral 17, the check column being designated 18, the deposit column 19, and the balance column 20. 90

In using the check book whenever a check is drawn, the transaction is entered on the stub sheet 14, and the amount is set down in the check column. Whenever a check is received it is indicated under the heading of 95 "Credit," and the amount of check is indicated in the deposit column. After the first stub sheet has been filled, the resulting balance 21, together with the totals of checks and deposits are entered thereon and brought 100 forward to the next sheet. In posting up from this system, the amounts may be taken directly from the stub sheets and transferred to the ledger.

From the foregoing it will be obvious that 105 with the use of a check book made in accordance with my invention, a business house will be able to determine at a glance the condition of their bank account, and when the bank book is returned for inspection, unless the 110 balances agree, there is an error somewhere which can be readily traced.

Having thus described the invention, what I claim is:

In a device of the character described, a temporary binding comprising cover members, a flexible back secured to said members, and the latter having slots therein, metal strips for reinforcing said slots, metal loops connected to the back by bolts and winged nuts, said loops being adapted to pass through

a series of bank checks and detachable stub sheets.

In testimony whereof, I affix my signature in presence of two witnesses.

LLOYD C. REEDER.
